ELECTRIC SWITCH LOCK FOR RAILROADS

Andrew Langdon, Brighton, N. Y., assignor to
 General Railway Signal Company, Rochester,
 N. Y.

Application January 7, 1946, Serial No. 639,612

11 Claims. (Cl. 246—159)

1

This invention relates to a locking device, and it more particularly pertains to an electric lock for limiting the hand operation of a railway track switch.

It is desirable where certain turnout tracks and outlying track switches connect to main line tracks, to lock such switches against operation under unsafe and unauthorized conditions. If these switches are frequently used they may be power operated, and the electric locking of such switches is contained in the means for power operation, but if the switches are not used frequently enough to warrant the expense of a power operated switch mechanism and its control circuits, they may be hand operated with electric lock mechanisms applied to allow hand throw operation only when the locks are electrically controlled from some remote point such, for example, as a dispatcher's office. Such remote control of the electric locks may be communicated from the dispatcher's office by a direct wire control, code communication system, or other communication means, dependent upon the requirements of practice. The lock mechanisms must of course be secured to the railway ties, and therefore they are subject to severe vibrations.

An object of the present invention is to provide an electric lock mechanism that will be reliable in its operation under the most severe conditions of vibration caused by passage of trains, and under the most severe conditions of abuse in the manual operation of the track switch with which it is associated.

Another object of the present invention is to provide emergency release means in a switch lock by which a trainman, upon proper verbal authorization from a dispatcher or other authorized person, may break a seal and cause the manual release of the electric lock to allow the hand operation of the track switch. Such procedure may be required upon the failure of the above mentioned remote control means due to bad weather, or other conditions adverse to remote electrical control.

Another object of the present invention is to provide a means for preventing the operation of the emergency release on the electric lock by unauthorized persons. This is accomplished by providing a mechanical interlock between the catch used for locking the hand throw lever in position and an emergency release cover. This arrangement provides that in order to break the seal of the emergency release and release the electric lock manually, it is first necessary to remove the padlock from the catch used for locking the hand

throw lever in position before the cover over the emergency release lever may be opened. In this manner it is possible to prevent unauthorized persons from tampering with the emergency release lever and possibly causing signals to display restrictive indications because of the opening of contacts in the electric lock mechanism. Conversely, it is provided that the padlock cannot be replaced unless the emergency release cover is closed.

Another object of the present invention with respect to the emergency release of the electric lock is to provide a check to insure the restoration of the seal on the emergency release lever each time after an emergency release operation of the electric lock has been required. This object is accomplished by allowing only partial restoration to normal of the electric lock mechanism after the hand throw switch has been operated and returned to its normal position subsequent to the release of the electric lock by the operation of its emergency release lever. This limited restoration of the lock holds contacts open in the lock mechanism to prevent the clearing of a signal governing traffic over the track switch with which such lock is associated. It is therefore provided that contacts on the switch lock which are normally closed to control a signal but which are opened by the emergency release means are held open until a signal maintainer or other authorized person who has a key to the cover of the switch lock opens such cover and mechanically releases the emergency controlled means for holding such contacts open. It is the duty of such maintainer or other authorized person to reseal the emergency release lever upon releasing the emergency control mechanism as described above.

Another object of the present invention with respect to the emergency release means is to provide an interlock between the emergency release cover and an emergency release lever to provide for automatic restoration of such lever to an intermediate position upon closure of the cover after such emergency release lever and has been moved to its fully operated position for unlocking the catch. Such arrangement provides that the emergency release lever must be moved to a position to allow the electric lock to be actuated to its locking position before the emergency release cover can be closed. Therefore before the padlock can be reinserted to lock the catch in its normal position the emergency release cover must be closed, because the catch cannot be fully restored to its normal position unless the emergency release cover is closed.

Other objects, purposes and characteristic features of the present invention will be in part obvious from the accompanying drawings, and in part pointed out as the description of the invention progresses.

In describing the invention in detail, reference will be made to the accompanying drawings, in which like reference characters are used to designate corresponding parts throughout the several views, and in which:

Fig. 1 shows a typical switch layout having a hand operated switch stand with its hand operation limited by an electric lock mechanism as provided by the present invention;

Fig. 2 is an end view of the electric switch lock with certain parts shown in cross-section, such section being taken along the line 2-2 of Fig. 1, and also along the line 2-2 of Fig. 3;

Fig. 3 is a side view of the electric switch lock with certain parts shown in cross-section, such sectional view being taken along the line 3-3 of Fig. 2;

Fig. 4 is an end view of a portion of the switch lock particularly showing the emergency release cover;

Fig. 5 is a sectional side view taken along the line 5-5 of Fig. 3 showing more particularly the relationship of the catch release cam to the latch and lock members with which its operation is associated;

Fig. 6 is a plan view of the part of the operating mechanism of the switch lock more particularly associated with the operation of the contacts, such view being a section taken along the line 6-6 of Fig. 3; and

Fig. 7 is a sectional view of a part of the emergency release lever and cover taken along the line 7-7 of Fig. 4.

With reference to Fig. 1, the general organization of the switch control apparatus is shown in which the track switch W is positioned by a throw rod 2 connecting the switch points 3 and 4 with the hand throw operating mechanism HT. The operation of the hand throw mechanism is provided by a throw bar 5, such bar being held in its normal position under normal conditions by the electric lock EL. The padlock P further secures the track switch against unauthorized operation by locking the catch 6 of the electric lock in its normal position. When the switch is operated, the hand throw bar 5 assumes the reverse position as indicated by dotted lines 7. Inasmuch as the hand throw mechanism HT may be of any suitable type, it is believed that description of such mechanism in detail will be unnecessary as such types of mechanisms are well known to those skilled in the art.

The hand throw bar 5 is normally held in its position as shown in Fig. 1 by the catch 6, and such catch is restricted in its operation by the detent 8 which is locked in a position by the padlock P to engage the catch 6 under normal conditions.

With reference to Fig. 2 the catch 6 is pivoted at the bar 9, and secured by the set screw 10 to such bar. Extending from the lower portion of the catch 6 is a forked member 11 for engaging the pin 12 of the nut 13 of the catch release rod CR. Such rod is disposed to operate longitudinally through the main case 14 of the electric lock at the point 15 and through the catch release case 16 at the point 17 to cause the operation of the catch release cam 18 which has a forked portion at its end 19 operated by the pivot 20 of the stud 21 of the catch release rod CR.

Upon the operation of the switch lock catch 6, the rotation of the catch release cam 18 is effective to operate the latch member 22 (see Fig. 5) to close contact 23 (see Fig. 6) for the energization of the electric magnet M. The movement of the catch release cam 18 is limited by the lock member 24 unless such lock member has been operated electrically to clear the detent 25 of the catch release cam 18 to allow the completion of the operation of the electric lock mechanism to its unlocked position. The lock member 24 includes a leaf spring 91 for reducing to a minimum the transmission of shock to the armature of the magnet, if an attempt is made to operate the switch before the magnet is energized; and it also includes a bumper 92 for absorbing shock under such conditions when the lock member 24 is pressed against the stationary stop 93 which is a part of the case 14.

To consider more specifically the construction to provide the above described mode of operation, with reference to Fig. 2, the catch 6 is formed with a treadle 26 at its base, and it is normally held in its locking position by the detent 8 which engages the top of the catch at 27 to restrict its operation. The detent 8 is normally locked to the case 16 by the padlock P as shown in Fig. 1, such detent being pivoted at the point 28. Upon the removal of the detent 8 by the switchman 25 after he has removed his padlock P, the biasing spring 29 (see Fig. 2) on the catch release rod CR is effective to cause the movement of the catch release rod to the left to a position to allow the catch release cam 18 to operate the latch member (see Figs. 5 and 6). The structure of the catch release rod CR to provide such mode of operation is provided by the rod comprising a stud 21 and nut 13 assembly which provides an arrangement by which the bushings 30 and 31 and the spring 29 can be assembled on the stud 21 within the spring compartment formed by the lower part of the switch lock case 14 in combination with the case 16 of the catch mechanism.

The bushings 30 and 31 are arranged to be movable along the shank 32 of the stud 21 within the limits of the shoulder 33 of the stud 21 and the shoulder 34 of the nut 13, respectively. The bushings 30 and 31 are large enough in diameter to be restricted at the points 15 and 17 of the casings 14 and 16 respectively, and thus provide a spring bias for the catch release rod to a center position. It will be noted that the position of the catch release rod as shown is in its normal position, and that the spring 29 is under tension to bias the catch release rod to its center position upon release of the catch member 6 by the detent 8. It will also be noted that the shoulder 34 of the nut 13 is so spaced with respect to the overall longitudinal movement of the catch release rod CR that it will cause compression of the spring 29 when the rod is moved beyond the position at which it is restricted by the lock member 24. This being the case, the catch member 6 is spring actuated from its full normal and its full released positions to a center position when it is mechanically disengaged from such extreme position.

In actual operation of the lock mechanism EL, the lifting of the throw bar 5 out of its normal position, with the catch 6 held down by the trainman applying pressure to the treadle 26 causes the bar 35 (see Fig. 1) to be moved under the catch member 6 through the opening 36 in the casing 16 (see Fig. 2) and thereby hold such catch in its released position throughout

the remainder of the operation of the track switch. It will be noted, with reference to Fig. 1, that the crank 37 on the hand throw mechanism HT operates the bar 35 longitudinally under the catch 6 whenever the hand throw lever 5 is in any position other than its full normal position.

With reference to Fig. 3, the catch release cam 18 has a shaft 38 extending longitudinally between the pivot points 39 and 40, and the cam 18 extends upwardly over the right-hand pivot 10 point at the point 41 with its top surface 42 (see Fig. 5) formed on a radius about the pivot point 40 and a part of such upper surface being cut at an angle as indicated by the dotted line at 43 to provide an operating surface to engage the roller 44 of the latch member 22. The cam surface 42 is also formed with a detent at the point 25 to engage the locking member 24, and restrict the operation of the catch 6 to its full release position unless the locking member 24 is raised to provide clearance for the detent 25.

With reference to Fig. 6, the latch member 22 is pivoted at the pin 45 and has normally closed and normally open contacts such as contacts 46 and 23 respectively secured thereto.

In a similar manner the lock member 24 is pivoted at the pin 45 and such member has normally open and normally closed contacts 47 and 48 respectively secured thereto by screws 49 and 50. With reference to Fig. 3, it will be noted that the lock member 24 includes an armature 51 which is attracted by the energization of the magnet M, and therefore the energization of the magnet M is effective to cause the lock member 24 to rotate about the pivot point 45 and to raise the end of the member 24 sufficiently to allow clearance for the detent 25 (see Fig. 5) of the catch release cam 6.

In order to insure that the latch and lock members 22 and 24 respectively will remain in their normal positions irrespective of severe conditions of vibration, a relatively stiff spring 52 is provided to bias the latch member to its normal position, and the latch member 22 is effective to hold the lock member 24 in its normal position because of the shoulder 53 formed at the left of the latch member 22 extending above the lock member 24 to force such member into its locking position. The relatively light spring 54 is effective to hold the lock member 24 in locking engagement when the latch member 22 is operated until such lock member is electrically actuated to a release position.

As a means for providing suitable connections to the contacts of both the latch and lock members 22 and 24 respectively, a terminal block 55 is secured at the top of the electric lock mechanism so that the terminals will be readily accessible when the cover is removed. Such block also provides support for the stationary part of the contacts. Along the side of the terminal block is a lamp receptacle 56 for the lamp 57. Such lamp is illuminated whenever the electric lock is energized to indicate to the trainman through the translucent insert 58 in the cover 59 when the switch can be operated.

To consider the manner in which the electric lock mechanism is controlled electrically, the raising of the latch member 22 to its operated position by the cam 18 is effective to close contact 23 (see Fig. 6) of such member and thereby close the local portion of the circuit for the energization of the magnet M, energy being applied from a remote point to the wire 81, through contact 23, and the two coils of the magnet M connected in series to the opposite potential of the 76 means at points 18. It will be noted that the

source of energy as applied to the wire 82. In accordance with the energization of the coils of the electromagnet M the attraction of the armature 51 of the mechanism causes the lock member 24 to be raised to allow clearance for the catch release cam detent 25 (see Fig. 5). In such operation, an obvious circuit is closed at contact 47 (see Fig. 6) to cause the energization of the lamp 57 to indicate to the trainman that the release of the electric lock has become effective.

It will be noted that normally closed contacts on both the latch member 22 and the lock member 24 are normally effective to close a portion of a signal control circuit. That is, with reference to Fig. 6, a portion of a signal control circuit has been illustrated which extends through contacts 46 and 48 of lock member 24 and latch member 22 respectively to provide that the signal thus controlled can be cleared only if the latch and lock members are both in their normal positions.

With reference to Figs. 3 and 4, an emergency release lever 60 is secured at one end by a screw 61 to a pin 62 extending through the case 14 of the electric lock, such pin being secured inside the case to an emergency release cam 63 having an angular surface 64 at the end for the engagement of the latch member 22 and the lock member 24 when the emergency release lever is operated.

The emergency release lever 60 is normally in the position shown in Fig. 4 with its end 65 adjacent the stationary post 66, and a seal 67 extending through registration holes provided for that purpose in these respective parts.

With reference to Fig. 3, the cap 68 is provided for covering the emergency release lever 60 and its seal 67. Such cap is pivoted at the pin 69 and formed with a circular detent 70 about the radius of such pin 69 for engaging the pin 71 which extends through the side of the case 14. The pin 71 is biased to a position in engagement of the detent 70 of the emergency release cover 68 by the spring 72 acting against the shoulder 90. By this arrangement, it is provided that the opening of the emergency release cover 68 can be effected only if the pin 71 can be free to travel longitudinally to the left. Such movement of the pin is normally restricted by the boss 73 on the side of the catch release cam 18 but, with reference to Fig. 5, an elongated hole 74 is provided in the catch release cam 18 to allow clearance for such pin as the cam is operated to an initiating position. In other words, in order to open the emergency release cover 68, it is first necessary to remove the padlock P, which secures the catch member 6 in its normal position, and remove the detent 8 from engagement with the catch member to allow the catch member to be operated toward its release position by the spring bias of 60 the catch release rod. Such operation is of course effective to cause the catch release cam 18 to be rotated in a counter-clockwise direction (see Fig. 5) so as to allow the pin 71 to move longitudinally within the elongated hole 74 in the cam 18. The length of the elongated hole is such as to allow the complete operation of the mechanism to a fully unlocked position.

With reference to Figs. 3 and 4, the pivot pin 69 for the emergency release cover is held in position by a bracket 75 secured to the case 14 by screws 76. Such bracket provides a housing around the detent 70. It is illustrated in Fig. 4, that the cover 68 and the detent 70 are secured to the pivot pin 69 by rivets or other suitable

spring 72 is not only effective to bias the pin 71 to its normal position to be in disengagement with the catch release cam 18, but such spring is also effective to hold the cover 68 tightly closed upon the cover gasket 79. It will also be noted that the operation of the pin 71 by the circular detent 70 is such that the bias of the spring 72 is applied to the cover until it is opened far enough so that the point 80 of the detent slips past the end of the pin 71. Beyond this point in the opening of the cover, the spring is relatively ineffective to cause the closing of the cover, and such cover will remain open in its fully opened position.

After considering the structure particularly related to the emergency release of the electric lock, consideration can now be given to the mode of operation of the electric lock under emergency release conditions. To initiate such emergency release, the trainman must first remove the padlock P from the detent 8, and release the detent 8 from the catch 6. The spring 29 is then effective to bias the catch release rod to its center position and thereby cause the catch release cam 18 to be operated to a position to allow the longitudinal movement of the pin 71 and thus allow the opening of the emergency release cover 68. The breaking of the seal 67 inside the cover then allows the lever 60 to be operated to cause the emergency release cam 18 to operate both the latch member 22 and the lock member 24 to their operated positions. The raising of the lock member 24 to its operated position allows clearance for the detent 25 on the catch release cam 18, and therefore the trainman can complete the release of the catch 6 by applying pressure to the treadle 26, thus allowing the hand operation of the switch throw bar 5.

When the switch is again restored after it has been operated under emergency release conditions, the complete restoration of the catch 6 to its normal position for the engagement of such catch by the detent 8, is restricted by the pin 71 if the emergency release cover 68 is still open because of such pin having been operated longitudinally within the elongated hole 74 of the catch release cam 18. Thus, it is required that the emergency release cover 68 be closed before the holes in the detent 8 and the case 16 can be aligned for receiving the padlock P.

It is further provided that the emergency release cover 68 cannot be closed to release the catch release cam 18 if the emergency release lever 60 is left in its fully operated position so as to hold the locking member 24 in its operated position. Such interlock is provided by the pin 83 in the emergency release cover 68 which is so placed as to strike the lever 60 and restrict the closing of the cover if the emergency release lever 60 is in its fully operated position.

It is further provided, with reference to Fig. 7, that the closure of the emergency release cover 68 is effective to automatically operate the emergency release cam 63 to cause such cam to release the locking member 24, and allow such member to be restored to its normal position. This mode of operation is accomplished by the provision of the bevel 86 provided on the end of the pin 83, and the bevel 94 provided on the emergency release lever 60. It will be readily apparent that from this arrangement, the closure of the cover 68 is automatically effective to operate the emergency release lever 60 to a position to cause the detent 84 of the emergency release cam 63 to assume a position between the locking member

24 and the latch member 22, such cam being restricted in its restoration to a full normal position by the detent 84 as will be hereinafter described. Inasmuch as the trainmen must close the emergency release cover before he can re-insert his padlock to lock the catch mechanism in its normal position, an assurance is obviously provided that the emergency release lever has been operated to a position to allow the restoration of the locking member 24 to its locked position.

In order to provide a means to check that the emergency release seal is replaced whenever such seal has been broken for an emergency release operation of the track switch, it is provided that the latch contact 46 (see Fig. 6) is not restored to its normal position to close the signal control circuit after the lock mechanism has been released by emergency operation. This mode of operation is provided by the detent 84 at the top of the emergency release cam 63 as shown in Fig. 4. In the operation of the emergency release lever 60, the detent 84 is moved past the point 85 at the end of the latch member 22, and upon the restoration of the emergency release lever following the desired operation of the track switch, the lever 60 can only be restored to a position in which the detent 84 will engage the latch member 22 at the point 85 and thereby cause the signal contact 46 of such latch member to be maintained open. It will be noted with reference to Fig. 6 that the lateral spacing between the end of the lock member 24 and the end of the latch member 22 is such as to allow the detent 84 to be retained between such members and yet allow the lock member 24 to be restored to its normal locking position. By this arrangement it is required that the maintainer, or some other authorized person be called to unlock the padlock P2 (see Fig. 3) and open the cover 59 of the electric lock mechanism and then manually release the emergency release cam 63 by lifting the latch member and operating the emergency release lever 60 to its full normal position. In this manner it is called to the attention of such authorized person that the seal has been broken and it is his duty to replace the seal at that time.

With reference to Figs. 4 and 7 the seal 67 is placed through a hole 88 in the post 66 when in registration with a hole in the pin 89 which is secured to the emergency release lever 60.

Having thus described an electric lock mechanism as one embodiment of the present invention, it is desired to be understood that this form is selected to facilitate in the disclosure of the invention rather than to limit the number of forms which the invention may assume, and it is to be further understood that various adaptations, alterations and modifications may be applied to the specific form shown to meet the requirements of practice without in any manner departing from the spirit or scope of the present invention except as limited by the appending claims.

What I claim is:

1. In an electric lock for hand operated track switches, a manual lever having normal and reverse positions for operating the points of a track switch, a catch having a normal position for locking said manual lever in a particular one of said positions, such catch being normally secured by a padlock in said normal position, a lock member for governing the release of said catch, manual emergency release means having normal and operated positions for allowing said lock member to release said catch when in its operated position, an emergency release cover effective

when closed to prevent the manual operation of said emergency release means to said operated position, and means for allowing the opening of said cover only when said catch is released from its normal position by the removal of said padlock.

2. In an electric lock for hand operated track switches, a manual lever having normal and reverse positions, a catch having a normal position for locking said manual lever in a particular one of its positions, a padlock, means for locking said catch in said normal position by the insertion of said padlock, a locking member for governing the release of said catch, manually operable emergency release means secured by a seal in a normal position but having an operated position for operating said locking member to allow the release of said catch, a cover effective when closed to prevent the manual operation of said emergency release means and the breaking of said seal, and means for allowing the opening of said cover only when said padlock is removed from said catch.

3. In an electric lock of the character described for a manual switch lever having normal and reverse positions, a catch having a normal position for locking said manual lever in a particular one of said positions, a locking member for governing the release of said catch, manually operable emergency release means effective when operated for rendering said locking member effective to release said catch, a cover effective when closed to prevent the manual operation of said emergency release means, locking means for securing said catch in said normal position by a padlock, and means controlled by said locking member for allowing said cover to be opened only when said catch is not secured by said padlock, such means being effective to allow the restoration of said padlock after the operation of said manual switch lever only if said cover is in said closed position.

4. In an electric lock for railroad track switches having a manually operable lever for moving the switch points, a catch effective to restrain said lever from manual operation except when said catch is released, an electromagnet at times acting to release said catch, a manually operable emergency release means effective when operated to release said catch regardless of said electromagnet, a cover effective to prevent access to said emergency release means unless it is opened, means connected to said cover for co-acting with said emergency release means for restoring it to a non-catch-releasing position when said cover is closed, and means for at times locking said cover in a closed position.

5. In an electric lock for a hand operated track switch, a manual lever having normal and reverse positions for operating the points of said track switch, a catch for locking said lever in a particular position, a lock member for governing the release of said catch, manual operable emergency release means having normal and operated positions effective when operated to allow said lock member to release said catch, a cover for said emergency release means effective when closed to prevent the manual operation of said emergency release means, and means for preventing the closure of said cover when said emergency release means is in said operated position.

6. In an electric lock of the character described for the locking of a manual switch operating lever in a particular position, a catch

for locking said manual lever in said particular position, a locking member for governing the release of said catch, manually operable emergency release means effective when operated for rendering said lock member effective to release said catch, a cover effective when closed to prevent the manual operation of said emergency release means, and locking means for securing said catch in said normal position by a padlock, such means being effective to receive said padlock only when said manually operable emergency release means is ineffective for allowing said lock member to release said catch.

7. In an electric lock having a hand operated track switch, a manual lever having normal and reverse positions for operating said track switch, a padlock, a catch for locking said lever in a particular one of said positions such catch being locked in its normal position by said padlock, a lock member for governing the release of said catch, manually operable emergency release means having normal, intermediate and operated positions and effective when moved to its operated position to allow said lock member to release said catch, a cover effective when closed to prevent the manual operation of said emergency release means, means for allowing the manual restoration of said emergency release means only to said intermediate position from

said operated position, and means for locking said cover in its closed position in accordance with the locking of said catch by said padlock.

8. In an electric lock of the character described for the locking of a manual switch operating lever in a particular position, a catch for locking said lever in said particular position, a lock member for governing the release of said catch, manually operable emergency release means having normal, intermediate, and operated positions effective when operated to allow said lock member to release said catch, a cover for said emergency release means effective when closed to prevent the manual operation of said emergency release means, means attached to said cover and acting upon the closure of said cover for causing said emergency release means to be restored from said operated position to said intermediate position, and contact means for allowing the clearing of a signal only when said manually operable emergency release means is in said normal position.

9. In an electric lock for railroad switches having a manually operable lever for moving the switch points, a catch having normal, half-normal, and released positions, said catch acting in its normal and half-normal positions to prevent operation of said lever but acting in its released position to permit free movement of said lever, an electric lock permitting movement of said catch between its normal and half-normal positions but preventing its movement between its half-normal and released positions except when such lock is energized, an emergency release means effective when manually operated to release said catch for operation to its released position, a cover preventing manual operation of said release means when said cover is in a closed position, means effective to prevent the opening of said cover while said catch is in its normal position, and means for at times locking said catch in its normal position, whereby said emergency release means cannot be operated unless said catch is unlocked and moved to its half-normal position.

10. In an electric lock for railroad track

switches having a manually operable lever for moving the switch points, a catch being biased to an intermediate position from either a normal or an operated position, said catch being effective in either its normal or intermediate positions to prevent the operation of said manually operable lever but being effective in its operated position to permit the free movement of said lever, an electromagnet having a lock member preventing movement of said catch from its intermediate position to its operated position except when said electromagnet is energized, an emergency release lever effective when manually operated from its normal position to an operated position to release said catch for operation from its intermediate position to its operated position, said emergency lever having an intermediate position in which said catch is not released, a cover member preventing access to said emergency lever except when said cover is in an open position, mechanical interlocking means preventing the opening of said cover member while said catch is in its normal position, contact means jointly operated by said emergency release lever in its intermediate or operated positions and by said catch in its biased intermediate position for opening a signal circuit, and a padlock for normally locking said catch in its normal position, whereby said contact means is operated on the removal of said padlock and is maintained operated by said emergency lever in its intermediate position.

11. In an electric lock for railroad track switches having a manually operable lever for moving the switch points, a catch being biased to an intermediate position from both normal and operated positions to which it may at times be manually operated, said catch acting in its normal and intermediate positions to restrain said manually operable lever against manual operation but acting in its operated position to permit the free movement of said lever, an electromagnet having a lock member preventing movement of said catch from its intermediate position to its operated position except when said electromagnet is energized, an emergency release lever having normal, intermediate, and releasing positions, said emergency lever being

effective in its releasing position to act on said lock member of said electromagnet so as to release said catch for movement to an operated position, said emergency lever being restrained 5 in its intermediate position by an auxiliary catch from restoration to its normal position after having once been operated to a releasing position, a cover member preventing access to said emergency lever except when said cover is in an open position, said cover member also having means requiring operation of said emergency lever away from its releasing position when said cover member is closed, mechanical interlocking means preventing the opening of said cover member while said catch is in its normal position and in turn preventing operation of said catch to its normal position unless said cover member is closed, contact means operated by said emergency lever in its intermediate or releasing positions and by said catch in its intermediate and operated positions for opening a signal circuit, a padlock for locking said catch in its normal position, and other means including another padlock for allowing manual operation of said auxiliary catch to permit the return of said emergency lever to its normal position only by an authorized person, whereby said contact means can only be operated to open the signal circuit when said padlock is removed 20 allowing said catch to assume an intermediate position, but said contact means being maintained operated to hold the signal circuits open when said emergency lever has been operated until said another padlock has been removed and said auxiliary catch has been released to allow the restoration of said emergency lever to its normal position.

ANDREW LANGDON.
